Specification of Letters Patent. Patented Jan. 13, 1920.

Application filed December 19, 1914. Serial No. 878,071.

To all whom it may concern:

Be it known that I, JAMES HENRY REID, a citizen of the United States, residing at 352 Mulberry avenue, in the city of Newark, county of Essex, State of New Jersey, have invented certain new and useful Improvements in Means Actuated by Alternating Electric Current for Controlling or Operating Electric Furnaces or other Mechanisms, of which the following is a specification.

This invention relates to apparatus actuated by electricity, and controlled by devices actuated by repulsion, induced by the action 15 of alternating current on a core acting against a non-magnetic armature, such as aluminium, copper, etc., for the production of distillation or sublimation by direct, fractional, destructive, or other means, of hydro- 20 carbons and production of products from residues. It has for one of its objects the provision of an apparatus for securing products of fractional or destructive distillation of hydrocarbon, such as bituminous coal, coal 25 tar, or other substance capable of yielding carbon by the action of heat and the making of products with what would be the non-volatile carbonaceous residues during the process of operation, such as calcium carbid, 30 which may be obtained by mixing calcium oxycompounds, such as calcium oxid or substances capable of forming the same such as calcium carbonate, with bituminous coal and subjecting the mixture to the action of elec- 35 tricity as hereinafter set forth. The invention further comprises exposing coal of the bituminous variety to the action of electricity of sufficient volume and intensity to operate against the resistance of the substance 40 employed and produce a temperature sufficient to evolve the product desired. It further comprises subjecting a mass of material to the action of electricity of progressively varying character so that varying degrees 45 of temperature may be generated within the charge and various products evolved and secured, such for example as the separate constituents of coal tar viz., benzol, toluol, xylol, etc., instead of coal tar *per se*. Or the whole 50 of the products may be driven off as a composite composition and the constituents recovered thereafter by fractional distillation.

As an illustration of the invention and

the manner in which it may be employed the production of tar and other ingredients or 55 substances evolved by the destructive and other distillation of bituminous coal together with the production of carbid, such as calcium carbid, will be taken, reference being directed to the accompanying drawing 60 in which:

Figure 1 shows a longitudinal vertical section of a furnace partly in elevation illustrating the electrodes, control device, and condenser, and,

Fig. 2 shows a diagrammatic view illustrating the control mechanism and electrical connections therefor, and illustrating the method of operation.

Similar numerals of reference represent 70 corresponding parts in the various views.

Referring to the drawings the numeral 1 indicates an electric furnace in which substances are treated or converted by heat or electrical action, comprising the receptacle 75 2 provided with the lining 3 and supported by the supports 4 by means of the bearing extensions 5.

The receptacle 2 is provided with a top or cover 9 through which pass the electrodes 10 80 and 11, which are held or supported by the supports or devices 12 and 13 by means of the insulation guides 43 and 44. The said electrodes pass through the cover 9 and are provided with the insulation sleeves 16 and 85 17. From the cover extends the outlet 18 provided with the fluid seal 19 and the revolving or movable damper or valve control 20.

The upper section of the cover 9 is also 90 provided with a sealed feed inlet 21, the removable seal of which may be removed and replaced for supplying ingredients to the apparatus and closing the apparatus during the operation thereof.

The lower section 2 and the upper section 9 are secured together by the clamps 22 and 23 actuated by the thumb screws 14. The lower section 2 of the converter is provided with a means 24 for making an electrical 100 connection to the converter of a character opposite to that of the electrodes 10 and 11, and which means includes a securing and releasing member for the electrical conductor. The outlet 18 with its seal 19 com- 105 municates with a removable conduit 25 oper-

ating through the swinging joint 26. This conduit communicates with an outlet 27 leading to the reservoir 28 and through which the condensed volatile or volatilized products 5 pass to the same, the reservoir 28 being provided with an outlet 29 for the permanent gases whereby said gases are conveyed to a reservoir (not shown).

The reservoir 28 for the distillate is provided with the outlet 31 controlled by the valve 33 at the lower part thereof, and the outlet 30 controlled by the valve 32 at a higher point for the removal of lighter products when the reservoir contains water.

15 The reservoir 28 is also provided with the legs or supports 34.

The receptacle 2 with its lining 3 is provided with the outlet or tap-hole 7 and the plug or closure 8 therefor, and the carbon 20 contact base or hearth 6. The wall of the discharge opening or tap-hole is also provided exteriorly with a spirally wound wire 58 of such character that its electrical resistance increases rapidly when heated and 25 which is employed to actuate and control the electrodes in order to maintain a substantially uniform temperature in the furnace and automatically adjust the electrodes for current control for this purpose as herein- 30 more fully set forth.

The cover 9 is also provided with the electrode feed and regulating motors or devices 35 and 36 which are in circuit with the reversing switch 49 (Fig. 2), the shaft of each 35 motor or electrode regulating device is provided with the spiral thread or worm 37 and 38, which engage the cog wheels 39 and 40, thereby revolving the screw bearing rods 41 and 42 which causes the guides 43 and 44 to 40 travel in an upward or downward direction, according to the direction of the revolution of the rod and simultaneously carry the electrodes 10 and 11 in like direction for feed or withdrawal to or from the furnace the guides 45 being supported by the carrying rods 13 and 12 passing through the sleeves 47 and 48. The electrodes 10 and 11 being attached or secured to the guides 43 and 44 by the binding screws 45 and 46.

50 In describing the furnace control mechanism operated through the automatic actuation of the electrodes reference is directed more particularly to Fig. 2 where parts of the electric furnace are shown connected with the control device in which the numeral 68 represents electrical conductors leading from a source of supply (not shown) and controlled by the switch 64. The wires 66 and 67 are leads to the electrodes 10 and 11 55 and the wire 65 to the pot or receptacle 1 of the furnace and its carbon electrode, hearth or base 6 by means of the terminal contact 24.

The electrode control motors 35 and 36 60 are in circuit with a reversing switch 49

provided with the repulsion devices 50 and 51 actuated by alternating current acting on non-magnetic armatures such as aluminium, copper, etc., which are in electrical connection with the contacts 52 and 53 respectively of the balance coils 54 and 55, said coils having an armature between them with a contacting arm 56 extending to and adapted to contact with the terminals 52 and 53. 70

Each of the coils 54 and 55 is in series with the resistance coil 57 or 58 respectively and the battery 59 and switch 60 when operating.

The power circuit 61 supplies current for operating the reversing switch and motors 80 for controlling the electrodes.

These two circuits constitute an electrical balance so that when both are energized and the resistance coils are maintained at the same temperature, the magnetic effect on the 85 armature 62 is *nil* and the arm 56 remains in the adjusted position shown in the drawing.

The furnace being cold the electrodes 10 and 11 are lowered into contact with the 90 hearth 6 thus establishing an electric current upon the closing of the switch in the circuit 68 and simultaneously the switch 60.

The resistance of the electrodes and hearth to the current raise their temperature and 95 consequently the resistance of the coil 58 thereby producing a greater flow of current in the resistance coil 57 and consequently disturbing the equilibrium of the armature 62 and causing the arm 56 to contact with 100 the terminal 52 and a flow of current through the repulsion device 50 reversing the switch 49 and changing the direction of the motors 35 and 36 thereby drawing the electrodes slowly apart and away from the 105 hearth.

The separating of said electrodes decreases the flow of current and consequently less heating effect and drop in temperature results which decreases the resistance of the 110 coil 58 and permits a balance in the coils 54 and 55 thereby bringing the arm 56 into contact with the terminal 53 at which time the current in the repulsion device 51 brings the reversing switch to its normal position. 115 The above action reverses the motors and draws the electrodes together thus increasing the current flow and a consequent rise in temperature. This cycle obtains so long as the furnace is in use. 120

The terminals 52 and 53 are provided with adjusting screws for regulation of the balance.

As an example of the process the production of calcium carbide from bituminous coal 125 and lime or calcium oxide and the recovery of the tar or volatile products evolved during the action of electricity on the composition will be taken.

A mixture of pulverized bituminous coal 130

- and calcium oxid in proportion of one hundred pounds of bituminous coal to 150 pounds of calcium oxid (pulverized) is thoroughly mixed and introduced into the 5 receptacle 2 through the opening 21, it is advisable to mix with this composition about 5% of powdered coke in order to reduce the initial resistance and provide a means for starting the passage of the electric current through the mass at a comparatively low voltage and also provide a means for initially heating the mass through the agency of electricity and also provide a means for rendering the mass more or less 10 porous so that the volatile products produced by the action of heat may be more readily evolved and discharged from the mixture. When the mixture has been introduced into the apparatus the supply 15 opening 21 is sealed and a current of electricity passed through the mixture from the electrodes 10 and 11 through the receptacle 2 by means of said electrodes and the contact 24 of the apparatus. As the current 20 passes through the mixture of bituminous coal and lime the heat generated by the resistance of the ingredients causes the evolution and distillation of various volatile products which condense and accumulate in 25 reservoir 28 from which they may be recovered and the different ingredients afterward secured by fractional distillation. Or 30 the electric current may be so regulated that each individual volatile ingredient produced 35 by the destructive distillation of the hydrocarbon in the converter 2 may be individually and separately secured during the process of destructive distillation, the temperature being regulated by moving the 40 electrodes through the insulating sleeves 16 and 17. When all the volatile products have been distilled off the residual non-volatile carbonaceous matter associated with the lime is heated to a high degree through the 45 passage of electricity and thereby converted 50 into calcium carbid which is finally removed from the receptacle 2 by removing the tap-hole plug 8, whereby the carbid is discharged while maintained in a molten condition 55 by the heat induced by the induction current passing through the induction coil 58. The outlet 18 is provided with a damper 60 which may be regulated by revolution to suitably check the outflow of the volatile products evolved during the process of operation, the conduit 25 may be raised and disconnected from the fluid seal device 19 which seal is preferably maintained by means of a low fusible metal. 65 By exposing the solid hydrocarbon, such as bituminous coal to the action of controlled electric currents, the internal resistance will produce intense heat so that the substance will be transformed throughout 70 in a regular and complete manner and will yield a larger percentage of products of more uniform character than in processes devised heretofore, so that the lighter hydrocarbons are not disrupted or "cracked" and such compounds as ammonia are more largely 75 produced and secured without decomposition.
- The nonvolatile carbonaceous residue remaining after the evolution of the more volatile and less carbon-containing products produced comprises very heavy hydrocarbon which reacts with a metal oxycompound, such as calcium carbonate or oxid, at elevated temperatures and produces calcium carbid directly from the coked lime 80 which is bonded with and by the heavy nonvolatile hydrocarbon.
- Other metal oxycompounds may be employed instead of calcium, such as barium, or other metal a carbid of which is desired, or 85 any nonmetal oxycompound a carbid of which is desired, such as silica for producing silicon carbid, or so called carborundum may be produced.
- The metal oxycompound may be a metal 90 oxid, such as calcium oxid, or substance capable of forming or yielding the same by the action of heat, such as calcium carbonate.
- The hydrocarbon employed is of the solid 95 variety under ordinary atmosphere conditions and preferably of the mineral species, or substances derived therefrom, such as bituminous coal, lignite, cannel coal, asphalt, or other solid mineral of organic origin.
- The various volatile products produced 100 by the action of electricity through the electrical resistance of the carbon-yielding substances operated on may be produced and collected as a composite composition and separated from each other by subsequent 105 fractional distillation or each may be secured as it is produced by maintaining the electrical condition necessary and capable of producing such independently until each has been evolved and the character of electricity 110 supplied altered to yield a next progressively higher carbon-containing product, whereby the products may be directly obtained separate from each other.
- Silicon carbid may also be made by mixing silica or silicates with the mineral hydrocarbon or carbon-yielding substance instead of metal carbid or any mixture of metal and nonmetal carbid may be produced. 115
- The term "carbid" employed herein is intended to include and does include broadly any nonvolatile carbid of a metal or nonmetal which may be produced by the action of a solid hydrocarbon and electricity on a 120 compound of such metal or nonmetal a carbid of which is desired, as herein set forth.
- The transformation of ingredients may also be induced and maintained by the action of electricity or an electric current on 125

an inert electrical resistor as a source of heat, such as silicon carbide, associated or communicating with the ingredient to be acted upon, as well as carbon, such as coke, 5 added or produced in the process, without departing from the spirit of the invention.

By inducing internal heat by electrical action, a more perfect and controlled transformation of the material acted upon into 10 the product desired may be accomplished, and the character of the product uniformly maintained without contamination, and also the yield of any individual product desired increased over that secured by any of the 15 means of the prior art, which depends upon the application or employment of externally applied heat for bringing about the destructive distillation and fractional separation of similar carbonaceous substances, and the 20 production of similar products.

As the conductivity of the mass acted upon increases by reason of the increasing non-volatile carbon residue, the electrical current is correspondingly regulated to 25 maintain a uniform and desired temperature. The conductivity of the initial charge may be augmented by associating the carbonaceous substances to facilitate the starting of the operation by inducing internal 30 heat, throughout the mass, whereby the transformation and evolution of volatile products may be obtained in the interior in an outward direction, thereby enhancing the porosity of the material and discharge of 35 volatile products without decomposition.

The control actuating device or operating member of the present invention is based upon a fact that many metals such as aluminium are repelled when subjected to the 40 action of alternating electric currents energizing a core, and when such non-magnetic metals as aluminium are employed as armatures they are repelled with a force corresponding to the character of alternating 45 current actuating the core of the device, and hence it will be seen that the aluminium armatures 70 and 71 will be repelled oppositely in accordance with the energizing of the coils 51 or 50 by means of alternating 50 current and the repulsion of the aluminium armature on either side actuates the switch 63 whereby the regulation of the electrodes in the furnace is automatically maintained by the motors 35 and 36.

55 Any or all substances capable of being repelled or acted upon in a manner like aluminium are intended to be included in the scope of the present invention which includes as a member for actuating the control 60 of electric furnaces a means or member actuated by repulsion action on the armatures induced by coils energized by alternating current, in contradistinction to and from magnetic action direct or through the me- 65 dium of a helix actuated by direct current.

Having now described my invention what I claim as new and desire to secure by Letters Patent is:—

1. An apparatus for making and securing products electrically, which comprises the 70 combination of a receptacle, electrodes therein, means for bringing the electrodes and receptacle into an electrical circuit, means including an armature of non-magnetic nature adapted to be acted upon by an 75 alternating current for repelling the same, temperature-governed means for regulating the movement of said armature, said armature controlling the operative distance of the electrodes when in use, and means for 80 reversing the movement of the electrodes while communicating with the controlling member.

2. An apparatus for making and securing products electrically, which comprises the 85 combination of a closed receptacle, electrodes therein, means for bringing the electrodes and the receptacle into an electrical circuit, means including an armature of non-magnetic nature adapted to be acted upon by 90 an alternating current for repelling the same, temperature-governed means for regulating the movement of said armature, said armature controlling the operative distance of the electrodes when in use, and means for 95 moving the electrodes communicating with the controlling member.

3. An apparatus for making and securing products electrically, which comprises the combination of a closed receptacle provided 100 with a condenser, electrodes in said receptacle, means for bringing the electrodes and the receptacle into an electrical circuit, means including an armature of non-magnetic nature adapted to be acted upon by an alter- 105 nating current for repelling the same, tem- perature-governed means for regulating the movement of said armature, said armature controlling the operative distance of the electrodes when in use, and means for moving the electrodes forward and backward 110 while in communication with the controlling member.

4. An apparatus for making and securing products electrically which comprises the 115 combination of a closed receptacle provided with a condenser, electrodes in said receptacle, means for bringing the electrodes and the receptacle into an electrical circuit, means including an armature of non-mag- 120 netic nature adapted to be acted upon by an alternating current for repelling the same, temperature-governed means for regulating the movement of said armature, said armature controlling the operative distance of 125 the electrodes when in use, and means for reversing the movement of the electrodes while communicating with the controlling member.

5. An apparatus for making and securing 130

- products electrically, which comprises the combination of a closed receptacle, electrodes therein, means for bringing the electrodes and the receptacle into an electrical circuit, means including an armature of aluminium adapted to be acted upon by an alternating current for repelling the same, temperature-governed means for regulating the movement of said armature, said armature controlling the operative distance of the electrodes when in use, and means for moving the electrodes communicating with the controlling member.
6. An apparatus for making and securing products electrically, which comprises the combination of a closed receptacle provided with a condenser, electrodes in said receptacle, means for bringing the electrodes and the receptacle into an electrical circuit, means including an armature of aluminium adapted to be acted upon by an alternating current for repelling the same, temperature-governed means for regulating the movement of said armature, said armature controlling the operative distance of the electrodes when in use, and means for moving the electrodes forward and backward while in communication with the controlling member.
7. In an electric furnace, the combination of an electrode moving mechanism with means for controlling such movement including a device for actuating the operative mechanism of an electric furnace, which comprises the combination of a non-magnetic armature with means for repelling the same, actuated by energy induced by an alternating current.
8. In an electric furnace, the combination of an electrode moving mechanism with means for controlling such movement including a device for actuating the operative mechanism of an electric furnace, which comprises the combination of a non-magnetic armature with means for repelling the same, actuated by energy induced by an alternating current for repelling the same, temperature-governed means for regulating the movement of said armature, said armature controlling the operative distance of the electrodes when in use, and means for moving the electrodes communicating with the controlling member.
9. In an electric furnace, the combination of an electrode moving mechanism with means for controlling such movement including a device for actuating the operative mechanism of an electric furnace, which comprises the combination of an aluminum armature with means for repelling the same actuated by energy induced by an alternating current.
10. In an electric furnace, the combination of an electrode moving mechanism with means for controlling such movement including a device for actuating the operative mechanism of an electric furnace, which comprises the combination of an aluminum armature with means for repelling the same actuated by energy induced by an alternating current, and means communicating with the mechanism to be actuated and the armature for accomplishing the same.
11. An electric furnace, comprising a receptacle, electrodes therein, means for supplying an alternating current thereto, and means for altering the distance between electrodes including a switch actuated by repulsion to lines of force induced by the alternating current.
12. An electric furnace, comprising a receptacle, electrodes therein, means for supplying an alternating current thereto, and means for altering the distance between electrodes including a switch actuated by repulsion to lines of force induced by the alternating current acting upon an aluminum armature.
- In testimony whereof I affix my signature in presence of two witnesses.
